UNITED STATES PATENT OFFICE.

THOMAS WALKER, OF PHILADELPHIA, PENNSYLVANIA.

DAMPER-REGULATOR.

SPECIFICATION forming part of Letters Patent No. 339,504, dated April 6, 1886.

Application filed October 7, 1885. Serial No. 179,203. (No model.)

To all whom it may concern:

Be it known that I, THOMAS WALKER, a citizen of the United States, residing in Philadelphia, Pennsylvania, have invented certain 5 Improvements in Damper-Regulators, of which the following is a specification.

My invention relates to that class of regulators in which a damper in the chimney, stack, or flue is closed when the steam in the boiler 10 reaches a certain pressure, and is opened when the pressure falls below the desired limit, the object of my invention being to render such an apparatus more sensitive in its operation than usual. This object I attain in the manner which I will now proceed to describe, reference being had to the accompanying drawings, in which—

Figure 1 is a view, partly in section and partly in elevation, of a damper-regulator having an attachment constructed in accordance 2c with my invention; and Fig. 2 is a sectional view, on a larger scale, of part of said attachment.

In Fig. 1, A represents part of a chimney or 25 stack, in which is a damper, A', the arm a of which is connected by a link, b, to the weighted arm B, which bears upon the stem d of a plunger, D, resting upon a flexible diaphragm, f, in a chest or box, F. Usually this diaphragm 30 is subjected to the pressure of steam, which enters the lower portion of the chest F through a passage, g, communicating, through a pipe, h, directly with the boiler, the diaphragm being consequently subjected at all times to the 35 full boiler pressure. The objection to this arrangement is, that it is not as sensitive in its action as is desired, a difference in pressure of several pounds being necessary in order to effect the closing or opening of the damper. In 40 order to overcome this objection, I use an attachment consisting of a casing, H, between the upper and lower portions, J J', of which is confined a diaphragm, i, connected to a block, m, the latter being secured to or forming 45 part of a rod, n, which passes through a nut, p, adapted to a threaded opening in the upper portion, J, of the casing, a spring, s, being confined between this nut and the block m, so as to exert upon the latter a downward 50 pressure, the force of which depends upon the adjustment of the nut. Screwed into the block m is a plug, v, to a central opening in which

is adapted the stem w' of a valve, w, this valve being adapted to a seat, x, in the lower portion, J', of the casing H, and being confined 55 vertically to the plug v by means of nuts w'', adapted to the threaded upper end of the stem w', the opening in the plug, however, being larger in diameter than the stem of the valve, in order to permit a slight lateral play of the 6c valve in the plug to insure the proper seating of the valve.

The chamber below the diaphragm i communicates through a pipe, y, with the steam-space of the boiler, the pipe h of the damper-regulator communicating with a passage, t, the mouth of which is closed by the valve w.

The pipe h has a cock, h', which is so constructed or so adjusted as to provide an opening of contracted area for the escape of steam 70 from the said pipe h at a point near the upper end of the same.

When the pressure of steam in the boiler is at or below the desired limit, the upward pressure upon the diaphragm i is not sufficient 75 to overcome the pressure of the spring s, and the valve w is consequently held to its seat, so that the diaphragm f in the chest F is free from pressure, the plunger D being consequently depressed under the action of the weighted arm 80 B, and the damper in the flue or stack being allowed to remain open, as shown in Fig. 1. As soon as the pressure in the boiler rises above the desired limit, however, the pressure of the spring s is overcome, the diaphragm i 85 raised, and the valve w lifted from its seat, so as to permit the steam to enter the pipe h, the diaphragm f of the chest F being consequently subjected to the full boiler pressure, so that the plunger D is elevated, and the damper 90 closed until such time as the pressure in the boiler falls to the desired limit, whereupon the valve w will be closed and the diaphragm f released from pressure, so as to permit the plunger D to fall and thus open the damper. 95

During all the time that the valve w is open there is a slight escape of steam from the cock h', and after the valve w closes this escape continues until the descent of the plunger D is completed, a more rapid descent being thus 100 permitted than if the steam were trapped in the chest F and pipe h, as in this case the plunger could only descend as the steam became condensed.

Even with the use of the cock h' there is on each operation more or less condensation in the chest F and pipe h , and in a short time this water of condensation will fill said pipe 5 up to the level of the cock, and will thereafter serve as the medium through which the pressure of steam in the boiler acts upon the diaphragm f . Said diaphragm may, therefore, without risk of deterioration, be made of rubber, which material is advisable on account of its elasticity, which permits the ready movement of the plunger in one direction or the other. The diaphragm i in the casing H , however, should be made of thin sheet metal, which 10 will withstand the action of the live steam from the boiler.

A weight acting upon the stem n may be used instead of the spring s , if desired; but the latter is preferred as more convenient.

20 In order to prevent the undue rise of the block m , such as would cause the straining of the diaphragm i , said block is provided with a flange, k , which, by contact with a seat in the upper portion, J , of the casing H , restricts 25 the rise of said block.

Instead of forming a reverse bend, as shown, the pipe h may be carried upward directly from the lower portion of the chest F , the construction adopted in all cases being preferably such as will permit the maintenance in 30 the pipe of a volume of water as the medium through which pressure is exerted upon the diaphragm f .

A piston may be substituted for the diaphragm f or i , and is considered the equivalent of the same, although the diaphragm is 35 preferred.

I claim as my invention—

1. The combination of the casing H , having a passage, t , and diaphragm i , the block m , 40 connected to said diaphragm, and the valve w , adapted to close said passage t , and having a slight lateral play in the block m , all substantially as specified.

2. The combination of the diaphragm i , the 45 block m , the plug v , secured to said block, the valve w , having a stem adapted to an enlarged opening in said plug, and the nuts w^2 , whereby said valve is confined vertically to the plug, all substantially as specified. 50

3. The combination of the damper-regulator, the casing H , having a diaphragm and valve, and the pipe h , connecting the damper-regulator and the casing H , and forming a water-reservoir between the two, all substantially as 55 specified.

4. The combination of the damper-regulator, the casing H , having a diaphragm and valve, and the pipe h , connecting the regulator and casing H , and having a cock, h' , as set forth. 60

5. The combination of the casing H , the diaphragm i , the block m , and its valve w , and a stop, k , whereby the rise of the diaphragm and valve is restricted, all substantially as 65 specified.

In testimony whereof I have signed my name to this specification in the presence of two subscribing witnesses.

THOMAS WALKER.
